UNITED STATES PATENT OFFICE.

ELZY M. WOLFF, OF MANSFIELD, OHIO.

DESIGN FOR A MONUMENT.

SPECIFICATION forming part of Design No. 33,318, dated October 2, 1900.

Application filed August 1, 1900. Serial No. 25,480. Term of patent 3½ years.

To all whom it may concern:

Be it known that I, ELZY M. WOLFF, a citizen of the United States, residing at Mansfield, in the county of Richland and State of Ohio, have invented and produced a certain new and useful Design for Monuments, of which the following is a specification.

The monumental design (illustrated by the accompanying perspective drawing) consists of a rectangular base A, a second or molded base B, resting upon the lower base. The die C is shorter than the base B on the horizontal line and inclining from all sides toward the top. Each end of the die is provided with the buttress D, the upper surface being carved. The vertical walls of each buttress are provided with raised geometrical figures F. Near the top of the die and extending around the same is cut the carved frieze G; but upon the face of the die and below the

name is a festoon H. The upper edge of the die is formed into a concave molding I, extending around the same. Resting upon the upper face of the die is a statue J, consisting of two figures—mother and child—the mother holding the child by the hand and looking backward, the child looking forward and one arm extended, pointing in the direction in which she is looking.

Having fully described my new monumental design, what I claim is—

The design for a monument substantially as illustrated and described.

In testimony whereof I affix my signature in presence of two witnesses.

ELZY M. WOLFF.
